UNITED STATES PATENT OFFICE.

HARRY L. DUNCAN, OF NEW YORK, N. Y.

BALING-PRESS.

SPECIFICATION forming part of Letters Patent No. 671,918, dated April 9, 1901.

Application filed February 16, 1901. Serial No. 47,569. (No model.)

To all whom it may concern:

Be it known that I, HARRY L. DUNCAN, a citizen of the United States, residing in the city of New York, county of Kings, and State of New York, have invented a new and useful Improvement in Baling-Presses, of which the following is a specification.

My invention relates to presses for forming a cylindrical bale from fibrous material; and it consists in a novel form of positive ejector therefor, by which the forming bale may be discharged from the press positively and at any desired rate, and also in the combination, with a novel form of press, of such an ejector used in connection with the same.

In my copending applications Serial Nos. 47,570 and 47,571, filed February 16, 1901, and Serial No. 48,130, filed February 20, 1901, I claim such of my inventions as are disclosed but not claimed in this case.

In the accompanying drawings, in which similar reference characters refer to the same parts in the several views, Figure 1 is an axial section through a press, showing one form of ejector. Fig. 2 is a detail sectional view, taken on the line 2 2 of Fig. 1. Fig. 1^a is a view showing a modified form of ejector-wheel, taken on substantially the central plane of said wheel. Fig. 2^a is a view perpendicular to the axis of the press, showing this same ejector-wheel. Figs. 3, 4, 5, and 6 show another form of ejector applied to various forms of presses, which are shown in axial section. Fig. 7 shows in axial section the ejector disclosed in Figs. 1 and 2 as applied to a press having a conical cap-plate.

In Figs. 1 and 2, A is a stationary cap-plate, having two radial feed-slots *a* formed in its top and communicating with the baling-chamber below. B is the baling-chamber, substantially cylindrical with a slight taper at the top. It is rotated by an integral gear *b*, which may be driven at any desired speed by a meshing gear. (Not shown.) The flange *H* at the top of the chamber serves to hold it in place against the top plate in connection with the collar *h*, which is screwed thereto. In suitable bearings *d* on the chamber are mounted a series of four short shafts *g*, to each of which are rigidly secured two ejector-wheels *E*, having teeth *e* and a skew-gear *G*, as shown. The wheels *E* project through the

slots *D* in the chamber and the cylindrical bodies of the wheels and the teeth *e* thereon are adapted to engage the forming bale in 55 the chamber and force it to rotate therewith and positively feed it therethrough. The gears *G* mesh with and are rotated by the face gear-teeth on the flange-gear *C*, rotatably mounted on the chamber *B* and held in 60 place by the collar *c*, secured to the chamber. The gear *C* is rotated at a suitable rate relative to the chamber *B* by gear-teeth on its edge that mesh with a driving-gear. (Not shown.) Just below the collar *c* the bottom 65 plate *F* of the frame encircles the chamber and forms a bearing for the lower end of the same. Heavy side pieces *f* connect the cap-plate *A* and plate *F*. The material to be baled is fed to the slots *a* in the usual manner, dragged through them, and compressed against the end of the forming bale, as is usual in this art. The downward pressure of the material under the cap-plate is resisted by the ejector-wheels *E*, which so grip the 70 cylindrical forming bale as to prevent it slipping past these wheels. The ejectors are rotated at any rate desired, and thereby regulate absolutely the density of bale formed. The modified form of ejector-wheel *E* (shown 75 in Figs. 1^a and 2^a) is adapted to impinge on the body of the bale, passing through the chamber, as is shown in Fig. 2^a, and the short stub-teeth *e'* are adapted to crowd their way into the surface of the bale without severing 80 the material of which it is formed, as the longer teeth would do. This ejector-wheel is adapted to be mounted upon a drive-shaft *g'* in the same manner in which the wheels *E* are mounted upon the drive-shaft *g*.

In Figs. 5 and 6 are shown presses of this same general type for producing a cylindrical bale formed of flat helical ribbons substantially perpendicular to the axis of the bale. They are shown as provided with a rotating 95 ejector-ring through which the forming bale passes having screw-threads formed on their inner surface adapted to engage the bale and to absolutely control the rate at which it moves through the press away from the cap-plate. 100 In Fig. 5 the cap-plate *A⁵* is stationary and is provided with feed-slots *a⁵*. A revolvably-mounted ejector-ring *E⁵* is mounted just beneath the cap-plate *A⁵* and is held against it

by a suitable annular abutment on the frame-piece F^3 , attached to the cap-plate by bolts, as shown. The gear G^5 is shown integral with the ejector-ring. The inner surface of this 5 ring is conical in contour and is formed with a helical ridge or ejector screw-thread e^5 upon it, which is adapted to engage the forming bale and hold it against the cap-plate with the desired degree of force. It is to be noted that 10 the depth of this screw-thread varies. The helical ridge gradually projects farther from the ring into the chamber through the first turn of the thread at the top of the ejector-ring. The revoluble baling-chamber B^5 is 15 mounted in a suitable recess in the framing F^5 and ball-bearings are indicated at both of these bearing-points. This baling-chamber has a cylindrical inner surface coaxial with the ejector-ring and is formed with a series of 20 bale-gripping fins g^5 , slightly tapered at their upper ends, so as to gradually force their way into the forming bale and projecting inward sufficiently to grip and positively rotate the forming bale at the same speed as the baling- 25 chamber. Gear b^5 is shown attached by suitable bolts to the baling-chamber to rotate it at any desired speed when driven by a suitable gear-pinion. The ejector-ring is also intended to be driven at any desired rate by a 30 gear which meshes with the gear G^5 . In Fig. 6 the framework of the machine consists of the piece F^6 , which is rigidly attached to the cylindrical baling-chamber B^6 by bolts, as shown. The cap-plate having a substantially 35 flat lower surface and being formed with feed-slots a^6 is revolubly mounted in this framework and is guided so as to be rotated by a gear C^6 , shown on the edge of said cap-plate. Just below the cap-plate and also revolubly 40 mounted in the framework is the ejector-ring E^6 , having a driving-gear G^6 upon it and having the ejector-screw e^6 formed integral therewith on its inner surface and projecting into the baling-chamber, so as to engage the forming bale and hold it against the cap-plate with the force desired. The ejector-ring is tapered 45 in this case so as to more firmly grip the bale. The stationary baling-chamber B^6 has suitable longitudinal fins g^6 , formed integral 50 therewith on its inner surface, so as to positively rotate the forming bale in unison therewith. It will be noted that these two presses are substantially identical, the only difference being in the relative motion of the various 55 parts.

The operation of the press shown in Fig. 5 is as follows: The material is suitably fed to the feed-slots a^5 and is dragged into them and simultaneously compressed against the upper 60 surface of the forming bale, which is positively rotated against the cap-plate by the rotating baling-chamber B^5 . The threads of the ejector are pressed into the substance of the bale, so that the bale is prevented from 65 moving through the ejector-ring faster than allowed to do so by the screw-feed of the ejector-threads e^5 , and the ejector-ring is made

sufficiently long in the direction of the axis of the press, so that these ejector-threads can have this function and so that they will sufficiently impinge on the forming bale to prevent any slip of the bale past them. As the bale passes out of the ejector-ring it is engaged by the positively-rotating baling-chamber B^5 , the ribs g^5 of which are pressed into 70 the bale-surface so as to insure its positive rotation with the chamber. The rate at which the baling-chamber is rotated determines the number of layers formed in the bale in a given time. The speed at which the ejector-ring is rotated determines the amount of feed of the bale through the press, and in an obvious manner therefore determines the bale formed, since as material is dragged into the feed-slot as long as the bale rotates beneath 75 the cap-plate material will be continually added to the forming bale, so that practically any density is obtainable in this press, and the rotation of the ejector-ring is so regulated as to produce the desired density in the bale, 80 material being fed constantly, of course, to the feed-slots.

The operation of the press shown in Fig. 6 is almost identical with that just set forth in connection with the press shown in Fig. 5. 95 The various parts—the cap-plate, ejector-ring, and baling-chamber—have identical functions, and their forms will be modified in this press, as in the one just described, to act properly upon the material to be baled. The 100 density is also similarly regulated by adjusting the relative speeds of the baling-chamber and ejector elements, and the same is true of the press shown in Fig. 1.

In Figs. 3 and 4 I have disclosed a modified 105 form of baling-press in which the cap-plate, instead of having a flat inner surface, has an inner surface substantially paraboloidal. This surface is generated by the revolution of a rectangular paraboloid about its axis, thereby forming a surface of revolution the cross-section of which is indicated by the axial section shown in these figures.

In Fig. 3, A^3 represents the cap-plate, having, as shown, a paraboloidal cross-section. 115 Two feed-slots a^3 are formed on opposite sides of the same on an axial plane. This cap-plate is stationary and is attached by bolts shown to the framing F^3 , which supports in suitable bearings formed by the collar C^3 the 120 baling B^3 . Just ahead of the baling-chamber—that is to say, between the chamber and the cap-plate—there is supported by the rear end of the cap-plate and by the collar f^3 , attached to the framing, an ejector-ring E^3 of 125 cylindrical inner surface and mounted coaxial with the cap-plate and baling-chamber. This ejector has formed thereon the helical screw-thread e , which projects farther and farther into the chamber at the end of the 130 ring nearest the cap-plate throughout the first turn of the thread. The ejector-ring E^3 is adapted to be rotated by the integral gear G^3 , formed thereon. A suitable driving-gear

meshes with this gear and is adapted to drive the same at any desired rate of speed. The baling-chamber B, which is adapted to be rotated by the gear b^3 , attached thereto by bolts, 5 as shown, has formed on its inner surface longitudinal gripping-fins g^3 , which extend parallel to the axis of the press and which are adapted to force themselves into the forming bale sufficiently to positively rotate the same 10 with the baling-chamber, which is driven at any desired rate of speed. The operation of this press is as follows: Material is fed into the feed-slot a^3 in any desired manner, and since the forming bale fills the interior of the 15 cap-plate A and presses against the same this bale, rotated by the chamber, serves to drag in additional material through feed-slots a^3 , which is added to and immediately compressed against the forming bale within the 20 cap-plate. If material is fed constantly to the feed-slots throughout their whole extent, it will be seen that flattened ribbons will be formed which will be compressed against the forming bale within the press and which will 25 assume a form which will conform to the inner contour of the cap-plate, and since these ribbons are continuous and since the bale must necessarily move away from the cap-plate through the press these ribbons will have a helical 30 form—that is to say, they will move about the axis of the press and at the same time move along the axis. Their exact shape in the bale will be substantially a curved surface formed by the revolution of the compressing-abutment of the cap-plate about the bale-axis and 35 its simultaneous uniform feed along the same. This will generate a surface which I call a "parabolic helicoid" if the compressing-abutment is a parabola whose axis is the axis of 40 the press. It will be manifest that these continuous layers of fibrous material—such, for instance, as cotton—will be at the outer surface of the bale substantially parallel to the bale-axis. This bale, therefore, when completed 45 will be a coherent or self-binding bale. The ribbon layers of which it is composed cannot expand radially because of the circumferential strength of the fibrous material of which they are formed. Also longitudinal 50 expansion is prevented because of the great friction between adjacent layers caused by the great radial pressure exerted in the bale. This bale, therefore, is a coherent mass substantially solid from the moment it is formed 55 just inside the cap-plate, and it is formed continuously as long as material is fed to the feed-slots and the bale rotated by the baling-chamber. This bale, therefore, as it moves 60 away from the cap-plate is gripped by the helical threads e^3 of the ejector, which, forcing themselves into the body of the bale, prevent any slip of the bale past them along the axis of the press. The speed at which the bale 65 can move away from the cap-plate is therefore determined by the rate at which the ejector-ring is rotated, because this screw-ejector feeds the bale through the press in exactly the

same way in which the screw would feed a solid cylinder of material having a screw-thread cut in it. The bale as it moves through the 70 baling-chamber is positively gripped by the baling-chamber fins g , which are pressed into the substance of the bale and firmly hold it against rotation relative to the baling-chamber. The number of layers formed in a given 75 time, as long as material is constantly fed to the slots a throughout their length, depends practically on the speed at which the baling-chamber B^3 is rotated. The density of the bale depends upon the speed at which the 80 ejector-ring is rotated relative to the bale, and the bale is therefore given any desired density. This is because material is constantly drawn into the cap-plate and is compressed into a volume determined by the rate 85 at which the ejector displaces the forming bale. It will be noted in this connection that there will be considerable friction of the bale against the inner surface of the cap-plate and against the cylindrical surfaces of the baling-chamber and ejector, which will resist the 90 movement of the bale axially to the press. Since the bale is coherent, the ejector can be operated so as to positively force the coherent bale through the press and draw it away 95 from the cap-plate, where the resistance to movement away from the point of the cap-plate is greater than the pressure of the cap-plate upon it, which would tend to force it along the axis of the press. The ejector in 100 the case of the coherent bale therefore positively governs the movement of the bale through the press whatever may be the conditions of resistance in the cap-plate. The fins g^3 on the baling-chamber are formed of 105 just sufficient size to properly grip and positively rotate the forming bale with the baling-chamber, and the size of the helical threads e^3 is made just sufficient to give the 110 ejector the proper grip on the bale and control the axial feed of the same through the press. If desired, the relative lengths of the ejector-ring and of the baling-chamber might be varied without materially affecting their 115 function.

In the press shown in Fig. 4 in axial section the cap-plate A^4 has the same form as that shown in Fig. 3. The inner surface of the cap-plate in both these cases may be made instead of a paraboloid of revolution a helical paraboloid between two adjacent feed-slots—that is to say, such a surface as will be generated by the revolution of a rectangular parabola about its axis and its simultaneous regular feed along its axis. This movement of such generatrix along the axis of the press would be designed so that it would be substantially equal in amount per revolution to the desired feed of the bale through the press per revolution, and in this case the 120 material passing through the feed-slots and being compressed against the parabolic end of the forming bale would be compressed at 125 once to its final form. No reexpansion of

this material would be allowed as it moved about the bale-axis until additional material was compressed upon it. In Fig. 4 the cap-plate is secured to the frame F^4 by suitable bolts. The baling-chamber is formed of a cylindrical ring B^4 just behind the cap-plate and is supported by the ring f^4 , secured to the framing. The gear b^4 , integral with the baling-chamber, serves to rotate the same at any desired speed when driven by a suitable gear. (Not shown.) Just back of the baling-chamber B^4 the ejector-ring E^4 is mounted and is held in position by a suitable flange secured to the rear end of the framing F^4 . Suitable ball-bearings are indicated for relieving the friction of the moving parts. The ejector-ring is driven by gear G^4 , secured to it, and is formed on its inner cylindrical surface with a helical ejector-screw e^4 , which gradually bites into the cylindrical surface of the bale and absolutely controls its feed through the press. The operation of this form of press is very similar to that shown in Fig. 3. The material fed constantly into the feed-slots a^4 is at once compressed against the parabolic head of the coherent forming bale within the press. The bale in this case is positively rotated at any desired rate by the baling-chamber B^4 , the longitudinal ribs g^4 of which are just sufficient in size to prevent rotation of the bale relative to the baling-chamber. After passing through the baling-chamber the bale is engaged by the ejector-screw e^4 , which bites into its surface and which prevents any axial slip of the bale past such screw. The bale is fed positively through the press at any desired rate by the revolution of this screw exactly as a solid mass would be. The density of the bale can be controlled in this case exactly as in the preceding form of press described.

In the press shown in axial section in Fig. 7 the cap-plate A^7 is integrally formed with the heavy plate C^7 and has its inner surface of substantially conical form. It is provided with two feed-slots a^7 along an axial plane, each extending the whole length of the conical inner surface. A heavy reinforcing-rib is formed around the tip of the cap-plate transverse to the plane of the feed-slots and gives sufficient strength to the cap-plate. The extent of this rib on the outer surface of the cone is indicated by dotted lines. The cylindrical baling-chamber B^7 is rotated by an integral gear b^7 at any desired speed. The flange H^7 is held in place against the plate C^7 by the bolted collar h^7 and supports the chamber revolvably against the cap-plate and coaxial therewith. A series of four shafts g are mounted in bearings d at the lower part of the chamber. Two spiked ejector-wheels E , whose gripping-teeth e are formed as shown, are fixedly attached to each shaft g , and a skew-gear G is also similarly attached to each shaft. These skew-gears all mesh with a large skew-gear on the face of C , revolvably held on the end of the chamber by the collar c secured

thereto. C is revolvable at any desired rate by gear-teeth on its edge. The plate F supports B^7 revolvably and is supported in turn by rigidly-attached side pieces f , also attached to top plate C^7 . The ejector-wheels E project through slots D into the baling-chamber to grip the bale within it. The cylindrical bodies of these wheels impinge on the bale and press longitudinal scores or grooves in it (see Fig. 2) and aside from the teeth e would grip the bale and absolutely prevent its rotation with respect to the chamber. The teeth e also force themselves into the bale and prevent its slipping past them, because these teeth are so large and numerous that the bale cannot tear or crowd past them in moving axially through the press. The form of ejector-teeth shown in Figs. 1^a and 2^a could be used on this press. The press is operated, after first forming a dummy bale by filling the chamber by hand, as is usual in this art, by constantly feeding fibrous material into the feed-slots a^7 . The forming bale within the cap-plate is rotated in close contact with the under surface of the same by the rotating baling-chamber and engages the material outside and constantly drags it through the feed-slots and continuously compresses it against the conical end of the forming bale. The bale is therefore built up of continuous flattened helical ribbons, one entering through each feed-slot, that is fed continuously and the surface of which is always inclined to the bale-axis at the same angle that the compressing-lips of the cap-plate are. This bale will be coherent or self-binding, since radial expansion of the bale is resisted by the circumferential strength of the fibrous material of which it is composed, as in the blanket-bale. Longitudinal expansion is prevented by the great friction between adjacent layers caused by the radial pressure exerted through the whole bale. This bale is a coherent mass as soon as it is formed under the cap-plate, and it is engaged and positively fed forward through the press by the ejector-wheels at any rate desired. The ejectors are adapted to either resist the outward axial pressure of the bale caused by the pressure of the cap-plate against it or, in case the frictional resistance of the bale against the chamber and cap-plate exceeds this axial pressure, the ejectors are adapted to positively withdraw the bale from the cap-plate and to pull the coherent bale away from the point of the cap-plate at the rate desired. These ejector-wheels, all of which are rotated in unison, serve to feed the bale axially through the press just as a series of gears would do meshing with a series of racks in a solid cylinder in the baling-chamber. The ejector-wheels form a series of rack-like indentations in the coherent bale and simultaneously feed the bale positively by engaging with these indentations. The density of the bale is regulated by adjusting the relative speeds of the chamber and of the ejectors. Material is constantly

fed to the feed-slots a^7 , and as long as the bale is rotated at the same rate beneath the cap-plate the material is drawn in and compressed upon the end of the bale at a practically constant speed. This type of press is self-feeding within wide limits of density of the bale. The axial displacement of the coherent bale by its axial movement away from the cap-plate is governed absolutely by the ejector-wheels, and the volume into which a given amount of material is compressed is thus varied at will. This is the case in all the presses described in this application, and the density of the material in the bale can be practically varied at will.

The presses shown in Figs. 1, 5, 6, and 7 are preferably operated in a vertical position—that is to say, with the axis of the press vertical—while the presses shown in Figs. 3 and 4 are preferably operated with the press-axis horizontal. I wish it to be understood, however, that any form of press can be operated in any position desired and that it is only necessary to give the parts the relative motions I have described and to feed material to the feed-slots constantly in any desired manner.

The rotary bale-governing elements which engage the forming bale and control its axial movement positively govern the axial movement of the bale past them. By "positively govern" I mean that the rotary governing elements move the bale past them at a definite rate under all ordinary conditions of operation independent of the exact direction or amount of axial pressure which the bale exerts upon such elements and independent of the exact density and physical characteristics of the bale. Where I use the terms "positively control," "positively feed," and "positively move" in reference to the axial movement of the bale the word "positively" has the same significance.

It will be noted that any form of cap-plate shown could be applied to any form of press which I have described in this case. For instance, the press shown in Figs. 1 and 2 could be provided with a cap-plate of parabolic form, such as is disclosed in Fig. 3, or this press might be provided with a substantially conical cap-plate, as is shown in Fig. 7, forming such an ejector-press as is disclosed in my application, Serial No. 48,130, filed February 20, 1901, or, in fact, with a cap-plate having an inner surface substantially of the contour of any surface of revolution and provided with suitable feed-slots along axial planes. A coherent or self-binding bale could manifestly be produced upon this form of press. In any of these presses the bale as it is formed can be suitably bound and covered by means such as is familiar to workers in this art, and which I will not describe, after the continuous cylindrical bale has been severed into suitable individual bales. I do not wish to be limited by the exact proportions of the mechanism disclosed in the drawings

in this case, since considerable departure could be made from the exact proportions shown without losing the advantages of my improved construction. The exact scope of my invention will be set forth in the appended claims.

Having now described my invention, what I claim is—

1. In a baling-press, an abutment having a feeding-passage; a relatively-rotating baling-chamber, a rotating ejector mounted thereon and movable relative thereto and means to rotate said ejector to control the feed of the bale through the press.

2. In a baling-press, a cap-plate having a feeding-passage therein; means to rotate a forming bale with respect to said cap-plate, and a rotating member in connection with said rotating means and actuating means for the same for positively feeding the forming bale away from said cap-plate at any desired speed.

3. In a baling-press, a cap-plate having a feeding-passage the inner surface of which is substantially a surface of revolution; means for rotating the coherent forming bale with relation thereto, and rotary means in connection therewith for positively withdrawing said coherent forming bale axially from the cap-plate at any desired rate.

4. In a baling-press, a cap-plate having a feeding-passage; a relatively-rotating bale-chamber and rotary means past which the bale passes to positively regulate its axial movement away from said cap-plate.

5. In a baling-press, a cap-plate having a feeding-passage; a relatively-rotating baling-chamber; rotary means projecting into said chamber for positively regulating the axial feed of the forming bale with respect to the cap-plate whereby a continued production of the forming bale is allowed.

6. In a baling-press, a cap-plate having a feeding-passage; a bale-rotating element and rotary means for positively regulating the axial feed of the bale away from such cap-plate in such manner that the continuous axial feed of such bale is never interrupted during the operation of the press.

7. In a baling-press, a cap-plate having a feeding-passage; a relatively-rotating baling-chamber; a rotary ejector mounted thereon adapted to engage the outer surface of the forming bale and positively regulate its axial feed away from the cap-plate and means to actuate said ejector.

8. In a baling-press, a cap-plate having a feeding-passage; a relatively-rotating baling-chamber; and rotary means and actuating mechanism for such rotary means mounted thereon and provided with bale-gripping projections whereby the axial feed of the bale through the chamber is positively regulated.

9. In a baling-press, a cap-plate having a feeding-passage; a relatively-rotating baling-chamber; a rotary ejector provided with bale-gripping members whereby the axial feed of

- the forming bale away from said cap-plate is positively regulated and means to actuate said ejector.
10. In a baling-press, a cap-plate having a feeding-passage; a relatively-rotating baling-chamber; rotary means mounted thereon and actuating mechanism for such rotary means, and bale-gripping members mounted upon such rotary means whereby the pressure of the forming bale against the cap-plate may be suitably regulated.
11. In a baling-press; a compressing-abutment having a feeding-passage; a rotary baling-chamber movable relatively thereto; an ejector-wheel revolubly mounted on said baling-chamber and means to actuate and regulate the movement of said ejector-wheel whereby to positively regulate the axial feed of the forming bale away from said abutment.
12. In a baling-press, a cap-plate having a feeding-passage therein; a relatively-rotating baling-chamber; an ejector-wheel mounted on said chamber so as to rotate in a substantially axial plane; and means to rotate and to regulate the movement of said wheel.
13. In a baling-press, a cap-plate having a feeding-passage; a relatively movable baling-chamber; means to rotate the same with respect to the cap-plate; an ejector-wheel mounted on said baling-chamber so as to rotate in a substantially axial plane; means thereon adapted to impinge upon the surface of the forming bale and means to rotate and to regulate the rotation of said ejector-wheel.
14. In a baling-press, a cap-plate having a feeding-passage; a relatively-rotating baling-chamber; a spiked ejector-wheel mounted on said baling-chamber and means to move and means to regulate the movement of said ejector-wheel.
15. In a baling-press, a cap-plate having a feeding-passage; a relatively-rotating baling-chamber adjacent thereto; a spiked ejector-wheel revolubly mounted on said baling-chamber and the body of the wheel projecting thereinto, and means to regulate the movement of said ejector-wheel.
16. In a baling-press, a cap-plate having a feeding-passage, a relatively-rotating baling-chamber; an ejector-wheel mounted upon said baling-chamber and projecting into the same; bale-gripping projections on said wheel and means to regulate the movement of said wheel.
17. In a baling-press, a cap-plate having a feeding-passage; a relatively-rotating baling-chamber; a series of ejector-wheels mounted thereon and adapted to engage the forming bale therein, and means to cause these wheels to move at the same rate of speed.
18. In a baling-press, a cap-plate having a feeding-passage, a relatively-rotating baling-chamber; a series of ejector-wheels mounted thereon and adapted to engage the forming bale; and means to rotate all of said wheels at the same rate of speed.
19. In a baling-press, a cap-plate having a feeding-passage; a relatively-rotating baling-chamber; a series of ejector-wheels mounted thereon and adapted to engage the forming bale and fast to each of said shafts; and means to rotate all of said shafts at the same rate of speed.
20. In an ejector for a baling-press; a series of bale-gripping ejector-wheels; a series of skew-gears operatively connected therewith; a single coating skew-gear meshing with all of said skew-gears and means to rotate said last-named skew-gear.
21. In an ejector for a baling-press; a series of shafts lying in substantially the same plane transverse to the axis of the press; a bale-gripping ejector-wheel fast on each of said shafts; a skew-gear also fast on each of said shafts, a large skew-gear meshing with all of said skew-gears, and means to rotate said large skew-gear at any desired speed relative to said series of shafts.
22. In an ejector for a baling-press, a series of shafts lying in substantially the same plane transverse to the axis of the press; a bale-gripping ejector-wheel fast on each of said shafts; a skew-gear also fast on each of said shafts, a large skew-gear meshing with all of said skew-gears, and means to rotate said large skew-gear at any desired speed relative to said series of shafts.
23. In a baling-press, a cap-plate having a feeding-passage; a relatively-rotating baling-chamber; means for rotating the same at any desired speed; a series of shafts revolubly mounted upon said chamber in substantially the same plane transverse to its axis; a bale-gripping ejector-wheel on each of said shafts adapted to engage the bale within the chamber; a skew-gear also fast on each of said shafts; a large skew-gear engaging all of said skew-gears and revolubly mounted on said baling-chamber, and means to drive said large skew-gear at any desired speed relative to said chamber.
24. In a baling-press, a slotted cap-plate having a substantially conical inner surface; bale-rotating means movable relatively thereto; a bale-gripping ejector mounted on said bale-rotating means, and means to rotate said ejector at any desired speed so as to withdraw the coherent bale formed within the cap-plate from the same.
25. In a baling-press, a cap-plate having a feeding-passage and having a substantially conical inner surface; a baling-chamber rotating relatively thereto; a rotary ejector mounted on said baling-chamber, and means to rotate said ejector at any desired speed so as to withdraw the coherent bale formed within said cap-plate from the same.
26. In a baling-press, a cap-plate provided with a feeding-passage, and having a substantially conical inner surface; a baling-chamber rotatable with relation thereto; a spiked ejector-wheel mounted on said baling-chamber, and means to rotate said ejector-wheel so as to withdraw the coherent bale formed within said cap-plate from the same.
27. In a baling-press, a relatively-rotating baling-chamber and cap-plate having a feeding-passage therein, the interior of said cap-

plate being substantially a surface of revolution so as to produce a self-binding bale; a series of ejector-wheels mounted on the baling-chamber; projections upon said wheels which positively grip the bale passing through the chamber and means to regulate the movement of all of said wheels.

28. In a baling-press, a cylindrical baling-chamber; a relatively movable cap-plate having a feeding-passage therein, the inner surface of said cap-plate being substantially a surface of revolution, so that the cylindrical bale formed therein will be coherent or self-binding; a series of ejector-wheels mounted substantially radially on the baling-chamber, and means to move all these wheels at the same rate.

29. In a baling-press, a cylindrical baling-chamber; a relatively movable cap-plate protruding therefrom, the inner surface of which is substantially a surface of revolution, said cap-plate being provided with feeding-passages, and its form being such as to make a coherent or self-binding bale; an ejector-wheel mounted on said chamber and its periphery protruding through the side of the same so as to positively grip the cylindrical surface of the forming bale; and means to revolve said ejector-wheel at any desired rate.

30. In a baling-press for forming a self-binding cylindrical bale, a baling-chamber; a relatively movable cap-plate protruding therefrom and being provided with a feeding-passage; an ejector-wheel mounted on said chamber and projecting through the side of the same; gripping projections formed upon the said ejector-wheel, and means to positively move said ejector-wheel at any desired rate.

31. In a baling-press for producing a self-binding bale, a cylindrical baling-chamber; a relatively movable cap-plate having a feeding-passage therein, the inner surface of said cap-plate being substantially conical; a series of ejector-wheels mounted upon said baling-chamber and projecting within the same and means to positively move all said ejector-wheels at the same surface speed.

32. In a baling-press, means to rotate a forming bale, means to add material to the end of the bale and simultaneously compress it against the same and rotary means to positively govern the movement of the forming bale away from the compressing means.

33. In a baling-press, means to rotate a forming bale, means to compress additional material against the end of said forming bale and rotary means to positively govern the axial movement of said forming bale.

34. In a baling-press, a cap-plate having a feeding-passage, the inner surface of said cap-plate being substantially a surface of revolution, means to rotate a coherent forming bale in connection therewith and rotary means in connection with said rotating means

to positively govern the axial feed of said coherent forming bale.

35. In a baling-press, bale-forming means, a series of bale-gripping bale-governing wheels past which the bale moves arranged to engage the forming bale moving past them and means to cause all of said bale-gripping wheels to rotate at the same surface speed. 70

36. In a baling-press, bale-forming means, a series of bale-gripping wheels and means to rotate all of said wheels uniformly at any desired rate of speed. 75

37. In a baling-press, bale-forming means, a rotary bale-governing element, bale-gripping members upon said element arranged to engage the forming bale moving past said ejector element and means to rotate said ejector element with respect to said forming bale. 80

38. In a baling-press, bale-forming means, a rotary ejector arranged to impinge upon the bale and means to positively govern the rotation of said ejector whereby to positively govern the longitudinal movement of said bale. 85

39. In a baling-press, bale-forming means, a rotary bale-engaging element having bale-gripping projections thereon, and arranged to impinge upon the bale and means to permit the movement of said rotary bale-engaging element to cause said element to positively govern the longitudinal movement of the bale. 90

40. In a baling-press, bale-forming means, a cylindrical bale-governing element having bale-gripping projections thereon and means to permit the movement of said bale-governing element so that said element positively governs the longitudinal movement of the bale. 100

41. In a baling-press, bale-forming means, a series of cylindrical bale-gripping elements arranged to engage the bale and means arranged in connection with said bale-gripping elements to positively govern the movement of the bale through the press. 105

42. In a baling-press, bale-forming means and a rotary bale-governing element impinging upon the bale to positively govern the movement of the bale through the press.

43. In a baling-press, bale-forming means, a rotary bale-governing element mounted in a fixed relation to said bale-forming means to impinge upon the bale and to positively govern the movement of said bale away from the bale-forming means. 115

44. In a baling-press, means to add compressed material to the end of a forming bale, a rotary bale-governing element mounted at a fixed distance from such end of the forming bale arranged to impinge upon said forming bale and acting to positively control the movement of said forming bale longitudinally of the bale. 120

45. In a baling-press, means to add compressed material to the end of a forming bale, 130

a series of bale-governing elements mounted at a fixed distance from said end of the forming bale, to impinge upon the forming bale and to positively control the longitudinal movement of the bale.

46. In a baling-press, means to add compressed material to the end of a forming bale, a series of rotary bale-governing elements arranged to impinge upon the bale moving past them and mounted at a fixed distance from said end of the forming bale, and means in connection with said bale-governing elements acting to constrain them to move at the same surface speed.

47. In a baling-press, means to supply compressed material to one end of a forming bale and rotary means impinging upon the bale to positively govern the longitudinal movement of the bale.

48. In a baling-press, means to rotate a forming bale, means to apply compressed material to one end of the same, and rotary means to positively govern the axial movement of said bale whereby to regulate the pressure of said forming bale against said means for applying compressed material.

49. In a baling-press, a cap-plate having a suitable feeding-passage therein, means to rotate a forming bale relatively thereto and a rotary member past which the bale moves to positively govern the axial movement of said bale relatively to said cap-plate.

50. In a baling-press a cap-plate having a feeding-passage therein, a relatively-rotating baling-chamber and rotary means to engage the cylindrical surface of the forming bale and positively regulate the axial movement of the bale away from said cap-plate whereby to control the density of said bale.

51. In a baling-press, means to add com-

pressed material to the end of a cylindrical bale whereby to form a continuous cylindrical bale of compressed material, a rotary bale-gripping member arranged to engage said bale and past which said bale is allowed to move, such bale-gripping member acting to positively regulate the longitudinal movement of the bale past the same.

52. In a baling-press, a rotating baling-chamber to rotate a forming cylindrical bale therein, means to add compressed material to the end of said forming bale, a number of bale-governing elements mounted upon said chamber and arranged to impinge upon the bale within the chamber and means whereby all of said elements are constrained to rotate at the same surface speed.

53. In a baling-press, a rotating baling-chamber, means to rotate said baling-chamber whereby to rotate the forming bale within the chamber, means to add compressed material to one end of the bale, a rotary bale-gripping wheel mounted upon the chamber and projecting within the same to positively regulate the axial movement of the bale through the chamber.

54. In a baling-press, bale-forming means a number of rotary bale-gripping elements arranged to impinge upon the surface of the bale and means connected to said elements whereby all of said elements move at the same surface speed.

In testimony whereof I hereto affix my signature, in the presence of two subscribing witnesses, this 15th day of February, 1901.

HARRY L. DUNCAN.
